ATT'YS.

UNITED STATES PATENT OFFICE.

CHARLES KIDNER MILNE, OF HAMILTON, ONTARIO, CANADA.

WEIGHING MACHINE.

1,403,704.

Specification of Letters Patent. Patented Jan. 17, 1922.

Application filed February 3, 1920. Serial No. 356,020.

To all whom it may concern:

Be it known that I, CHARLES KIDNER MILNE, of the city of Hamilton, in the county of Wentworth, Province of Ontario, Dominion of Canada, have invented certain new and useful Improvements in Weighing Machines, of which the following is the specification.

My invention relates to improvements in weighing machines and the object of the invention is to devise simple, compact and strong dial attachment which may be applied to any of the ordinary platform scales so that the weight on the platform may be registered on a clock-dial; a further object is to render the connections between the platform and the dial entirely free from spring members; a further object is to provide means for obtaining in the machine any desired degree of sensitiveness; and a still further object is to provide such a mechanism in which any adjustment made will be permanent.

My invention consists of the construction and arrangement of parts all as more particularly described and illustrated in the accompanying drawing, in which:

Figure 1 is a back view partly in section showing my invention applied to a platform scale with the various parts in the position occupied when the indicating needle is at zero.

Figure 2 is a similar view showing the parts in the position occupied when the indicating needle has rotated through 180° of the dial.

Figure 3 is a general front view showing the clock dial.

Like characters of reference indicate corresponding parts in the different views.

1 indicates the base of the scales and 2 the weighing platform thereof. 3 indicates a hollow upright standard connecting the base 1 to the horizontal frame member 4. 5 is an upright standard carried by the frame 4 and supporting the dial 6. 7 is a shaft supported in bearings in the standard 5 and carrying at its forward end the indicating needle 8 and intermediately of the bearings 50 the toothed pinion 9. These bearings may be of either the plane, ball or other type. 10 is a fulcrumed lever rotatably supported intermediately of its length by the standard 12 at the point 11. I have shown a knife edge at this point but a journal end bearing or some other suitable means of support might be

used. The segmental toothed portion 13 at the inner end of the lever 10 engages the toothed pinion 9. The knife edge 14 is provided adjacent to the outer end of the lever 10. 15 is a weight adjustably connected to the inner end of the lever 10 by means of the arms 16 and 17, the latter of which is provided with a threaded portion 18. 19 is a standard carried by the frame 4. 20 is a lower lever fulcrumed adjacent to one end by the knife edge 21 engaging the upper face of the standard 19. 22 is a knife edge carried by the lever 20 adjacent to the end thereof remote from the knife edge 21. 23 and 24 are knife edges carried by the lever 20 intermediately of the knife edges 21 and 22. 25 is a weight supported from the knife edge 23 through the links 26 and 27. The weights 15 and 25 are mutually opposed counterbalancing weights. 28 and 29 are links connecting the lever 20 to the platform 2 through the medium of the knife edge 24. 30, 31 and 32 are links connecting the knife edges 14 and 22. The knife edge 14 and the supporting point 11 are so arranged that when the mechanism is in the position shown in Figure 2, that is when the needle has made half a revolution of the dial, the faces of these knife edges and the axis of the shaft 9 all lie in one straight line. Further in this position the knife edge 14 is vertical. The knife edges 21, 22 and 24 carried by the lever 20 may be so arranged that they all lie in one straight line. The weight 15 is adjustable on the arm 17 and the weight 25 is preferably made hollow so that it can be readily altered by adding shot or similar material. 33 is any suitable outer casing supported on the frame 4 and adapted to enclose the complete mechanism.

The operation of my device is as follows:

The mechanism is first adjusted for the zero reading as illustrated in Figure 1. This is accomplished by engaging the pinion 9 with the upper portion of the toothed segment 13 so that the indicating needle points to zero on the dial. In this position the weights 15 and 25 must be in a state of equilibrium so that the weight 15 is freely supported.

It will now be seen that when a weight is placed upon the platform, the lever 20 is pulled downwardly through the links 28 and 29 and the knife edge 24. As a consequence, the knife edge 22 is pulled downwardly and this downward movement being carried by

the links 30 and 31 and 32 to the knife edge 14 causes the outer end of the lever 10 to move downwardly and the toothed segmental inner portion 13 to rotate upwardly 5 about the supporting point 11 and this causes the pinion 9 to rotate in the direction indicated by the arrow and with it the indicating needle 8. The relative length of the segmental portion 13 in respect to the 10 circumference of the pinion 9 is such that slightly more than one complete revolution of the pinion is permitted.

The dial is marked into any suitable number of equal graduations and by varying the weights 15 and 25 the capacity of the scale may be altered as desired. Thus we have the scale divided into fifty graduations and the weights 15 and 25 so adjusted that each of these graduations represents a pound 20 weight, the capacity of the scale will be fifty pounds. By increasing the weights 15 and 25 sufficiently each graduation can be made equal to two pounds so that the capacity of the scale would be one hundred 25 pounds.

Hitherto the pinion 9 of clock dial scales has been operated by a straight rack, but it is to be noted that by the provision of my circular segmental lever 10, fulcrumed at 30 the point 11, a much greater degree of sensitiveness is obtained. The reason for this being that when a rack is used it must be supported in some type of slide and must be kept in engagement with the pinion by some 35 pressure means. Thus there is considerable friction at this connection. Also the weight of the rack itself tends to operate against the action of the scale. In my device these difficulties are entirely eliminated as the 40 lever 10 being supported intermediately of its length the two portions thereof can be made to counterbalance each other so that the effect of gravity on the lever is nil. Further as the lever 10 and the pinion 9 are 45 rotatably supported the radial pressure existing at the point of engagement therebetween is almost negligible.

From the foregoing it will be seen that I have devised a very simple, strong and compact dial attachment which can be fitted to 50

any platform scale and by which the capacity of such scale can be altered at will.

In practice the adjustment to the weights 15 and 25 would be made when the scale is manufactured so as to provide a scale of a 55 certain capacity, but manufacture would be simplified as any one size of scale can be used in order to supply scales of various capacities. It will thus be seen that I can make all the component members of my scale 60 in large quantities and scales of various capacities will be identical with the exception of the weights 15 and 25 and the dial markings. It is of course to be understood that the feature above referred to applies only 65 within reasonable limits and in making scales of very large capacities stronger and larger members must be used than would be the case with the smaller type of counter 70 scales.

What I claim as my invention is:

In a weighing machine, the combination with the weight receiving element and the weight registering element, of a plurality of substantially parallel levers placed one 75 above the other, the lower of said levers being fulcrumed adjacent to one end thereof to the main frame of the machine, connecting means whereby said lever is actuated by the weight receiving element, the upper of said 80 levers being fulcrumed intermediately of its length on the main frame of the machine, connecting means between the free end of the lower lever and the adjacent end of the upper lever whereby the upper lever is actuated by the lower lever, a circular pinion 85 operating the weight registering element, the free end of the upper lever formed into a circular segmental toothed portion co-acting with the circular pinion, and a system of mutually opposed counter-balancing 90 weights carried by the upper and lower levers, the weight carried by the upper lever being adjustable whereby the sensitiveness of the machine may be altered as desired.

CHARLES KIDNER MILNE.
